UNITED STATES PATENT OFFICE.

BERNHARD GUSTAFSON, OF PLAINFIELD, NEW JERSEY, ASSIGNOR TO
UNITED PRINTING MACHINERY COMPANY, OF BOSTON, MASSACHU-
SETTS, A CORPORATION OF MAINE.

AUTOMATIC SHEET-RETARDING DEVICE FOR PRINTING-PRESSES.

No. 832,968.

Specification of Letters Patent.

Patented Oct. 9, 1906.

Application filed August 11, 1905. Serial No. 273,714.

To all whom it may concern:

Be it known that I, BERNHARD GUSTAFSON, of Plainfield, in the county of Union and State of New Jersey, have invented certain new and useful Improvements in Automatic Sheet-Retarding Devices for Printing-Presses, of which the following is a specification.

This invention relates to an improved automatic sheet-retarding device for printing-presses.

Figure 1 is a side elevation showing a portion of the printing-press equipped with my improved device. Fig. 2 is a top plan view of the parts shown in Fig. 1. Fig. 3 is a view similar to Fig. 1, showing the parts in position to be engaged by a moving sheet of paper. Fig. 4 is a view similar to Fig. 3, showing the position of the parts after their engagement by the sheet of paper and the retarding action of the device. Fig. 5 is a conventional view showing the relative position of the parts of the machine.

The same numerals of reference indicate the same parts in all of the figures.

In Fig. 5 I have illustrated in a conventional manner the feeding-tapes 1, the plate 2, printing-cylinder 3, and one of the guide-arms 14 of a printing-press. These parts, as shown, are of ordinary and well-known construction and require no detailed explanation.

While I have illustrated my improved retarding device as connected to the guide-arms 14, this is for the purpose of illustration only, and I do not wish to be understood as limiting myself to such a construction, as they may be employed anywhere where it is desired to retard a moving sheet, whether paper or other material.

10 11 represent two arms arranged upon either side of a disk 12, that is bolted or otherwise secured to the end of an arm 14, a spring 151, carried by said arm 14, being arranged between the arms 10 11, the ends of the arms 10 11 extending beyond the ring 151. To the end of the arm 11 is pivoted a pendulum 13, while a complementary pendulum 16 is pivoted to the end of the arm 10. 50 The pendulums 13 and 16 are pivoted near their upper ends and are free to swing on

their respective pivots. From the upper end of the pendulum 16 projects a finger 17, bent rearward and sidewise, as shown, toward the opposite pendulum. A like and complementary finger 18 is connected to the pendulum 13. The arm 11 in the rear of the pendulum 13 is provided with a stop 19. 20 represents a like stop on the arm 10 above the upper end of the pendulum 16. The stops 19 and 20, as shown in Figs. 1, 2, and 3, are for the purpose of preventing the pendulums from dropping to a neutral position and maintaining them in a position of stored power. The automatic retarding device being positioned either as shown in the drawings or at any other desired point, as the sheet of paper 40 which it is desired to retard approaches the pendulums, ordinarily with great speed, it engages the pendulums, 70 raising their rear ends and bringing the fingers 17 18 against the paper. The action of the paper in lifting the pendulums 13 and in the sudden pressure of the fingers 17 18 is sufficient to overcome the momentum of the sheet, it being understood, of course, that the pendulums 13 and 16 will be proportioned and weighted corresponding to the weight of the sheet or other article that is to be used to retard and to the speed of travel. As the paper engages the pendulums 13 16 and raises their lower ends, as shown in Fig. 4, the result is that the fingers 17 18 are made to suddenly engage the paper and press it for a very short period against the plate or tongue 85 2 or other bed over which the paper is moving, the pendulum in the next moment dropping back on the sheet and leaving the sheet free to move. The pendulum serves as means for operating the fingers 17 and 18, 90 and while in a sense the pendulum acts to retard the momentum of the sheet, yet the means relied upon by me for retarding are the fingers, they being strictly the retarding means, the weight being used as a means for 95 pressing the fingers against the paper.

In practice the sheets of paper 40 approach the guides 15 at a high rate of speed, and there is a tendency to buckle the sheets at this point against the guide. By my improved automatic retarding device this defect is overcome, the pendulums operating automatic-

ally to retard the sheets and bring them to as near a full stop as it is desired just before they come in contact with the guides 15. As the sheets approach the pendulums they are of course under the control of the tapes or other conveying means, and the latter keep in contact with the sheet just long enough after the action of the pendulums 13-16 to give the sheet such motion as may be necessary to bring it to the guides 15, but without the shock that exists where my retarding device is not employed. As shown in the drawings, the pendulums are arranged at such an angle with the travel of the sheets as not to deliver too much of a shock, permitting the sheets to lift the lower ends of the pendulums easily, depressing the arms 17-18 against the sheet. The retarding is effected by the sudden engagement of the arms 17-18 with the sheets for a short period, enough space being provided for the pendulums to drop back upon the sheet and lift the arms 17-18, thus allowing the sheet to move freely sidewise, the pendulums being the means by which such contact can be effected without undue shock to the sheet. While in the drawings a pair of pendulums is shown, it is to be noted that each acts independently of the other. I may employ one or a plurality of pendulums, as desired.

Having thus explained the nature of my invention and described a way of constructing and using the same, though without attempting to set forth all of the forms in which it may be made or all of the forms of its use,

what I claim, and desire to secure by Letters Patent, is—

1. In a paper-feeding apparatus, means for feeding independent sheets of paper, a finger normally out of the plane of the travel of the sheets, a pendulum arranged in the plane of the travel of the sheets, and connections between the pendulum and finger whereby the finger is caused to engage each sheet by the contact of the latter with the pendulum. 45

2. In a paper-feeding apparatus, means for feeding independent sheets of paper, a pendulum arranged to be engaged by a moving sheet of paper, and means operated by said pendulum to engage said sheet to retard the latter.

3. In a paper-feeding apparatus, means for feeding independent sheets of paper, and an automatically-acting retarding device arranged to be engaged and operated by a moving sheet of paper to check the speed of the latter. 35

4. In a paper-feeding apparatus, means for feeding independent sheets of paper, a retarding device arranged to engage a moving sheet of paper, and a stored power means connected to said device and arranged to be engaged by a moving sheet of paper to operate said device.

In testimony whereof I have affixed my signature in presence of two witnesses.

BERNHARD GUSTAFSON.
